CARL F. GOUDY, OF FLUSHING, NEW YORK, ASSIGNOR TO PACENT ELECTRIC COMPANY, INC., OF NEW YORK, N. Y., A CORPORATION OF NEW YORK

PHONOGRAPH ADAPTER

Application filed July 16, 1930. Serial No. 468,310.

The objects of this invention are to enable the quick conversion of phonographs such as used for talking pictures, over from the playing of the large 16" records to the playing of the newer, smaller 12" so-called "long playing" records and to accomplish this in a simple practical way with inexpensive easily installed mechanism.

The smaller, long playing records start nearer the center than the larger records. Consequently, a tone arm which is set for playing the larger records with the pickup needle substantially tangent to the sound groove at the start, will locate the needle in side of the tangent at the start of a smaller record, making the needle track incorrectly and giving it a tendency to jump out of the groove.

The present invention involves the provision of simple means for re-setting the tone arm to bring the needle nearer the record center and hence into the proper substantially tangential relation for the start of the smaller record grooves.

Other novel features of the invention and the details of construction will appear as the specification proceeds.

The drawing accompanying and forming part of the specification illustrates one practical embodiment of the invention, it being understood that the actual physical structure may be modified as regards this disclosure, within the broad spirit and scope of the invention.

Fig. 1 is a broken plan view illustrating the invention in use on a sound picture phonograph; Fig. 2 is an enlarged broken sectional detail view of the special adapter bracket.

In Fig. 1, the turntable of a phonograph is represented as 3, and the pickup unit is shown at 4 carried by a swinging arm 5 pivotally supported at its outer end on an outstanding bracket arm 6.

The pivotal support for the pickup arm comprises the pivot stud 7 screwed in one end of a link 8, the opposite end of this link being pivotally engaged on the bolt 9.

The bolt 9 is shown secured by nut 10 and washer 11 in a rubber bushing 12 seated in a socket 13 in the end of a supporting arm 6

and forms in fact, a replacement part for the pivot stud usually employed in this location as a mount for the tone arm for playing the 16" records.

To convert a machine designed for the playing of the larger records over to the proper relation of parts for playing the smaller records, therefore, with this invention, it is only necessary to take out the old pivot stud and rubber bushing seated in the socket 13 of the supporting arm and to replace that with the special mounting bolt 9 and bushing 12 carrying the link 8 with the offset pivot stud 7, arranged as in Fig. 1, with the link inclined inwardly, so as to bring the needle of the pickup into substantially tangential relation to the starting portion of the record groove. By turning the link on its mounting bolt, the distance between the needle and record center and the tangential relation of the needle to the beginning of the record groove may be very accurately set. If necessary to re-set the machine for the larger size records, this can readily be done by loosening nut 10 and turning the link 8 to carry the swivel stud 7 out to a position of the same radial distance from the turntable center as the bolt 9, the nut being then tightened to secure the mounting stud with the tone arm carrying the needle ready to cooperate with the larger record. The offset pivot stud 7, is preferably constructed similarly to the pivot stud which it replaces, so that the same swivel mountings indicated generally at 14 will suffice for either stud, the tone arm being shiftable from one to the other without any change of structure. The substitute parts are of simple sturdy and inexpensive design and the substitution is easily effected without requiring special tools or special mechanical skill.

What is claimed is:

1. An adapter for phonographs comprising a mounting bolt, a laterally extending arm supported by said bolt and a tone arm supporting pivot stud upon the free end of said arm.

2. As a new article of manufacture, a phonograph adapter, comprising a link, a mounting bolt engaged at one end of said

link and a tone arm supporting mount on the opposite end of said link.

3. A substitute mount for a phonograph tone arm, comprising a mounting bolt, a link extending in offset relation from said bolt and a short stud on said link and constructed to provide a pivotal mount for a phonograph tone arm.

4. In combination with a phonograph turntable and a tone arm mounting bracket, a bolt mounted in said bracket, a link secured by said bolt and extending in offset relation from the center of said bolt, a short stud fixed on said link and a tone arm swivelled on said stud.

5. In combination with a phonograph turntable and a tone arm mounting bracket, a bolt mounted in said bracket, a link secured by said bolt and extending in offset relation from the center of said bolt, a short stud fixed on said link, a tone arm swivelled on said stud, said link being pivotal about the bolt center to different angular relations to enable setting of the tone arm pivot to different radial distances and inclined relations to the turntable center to enable setting of a pickup unit on the tone arm to substantial tangential relation to the starting points of different record grooves.

30 In testimony whereof I affix my signature.
CARL F. GOUDY.
